UNITED STATES PATENT OFFICE.

FREDERICK WM. RIESS, OF PHILADELPHIA, PENNSYLVANIA.

AUTOMATIC EXPANSION VALVE-TRAP.

1,036,006.

Specification of Letters Patent. Patented Aug. 20, 1912.

Application filed August 9, 1911. Serial No. 643,252.

To all whom it may concern:

Be it known that I, FREDERICK WM. RIESS, a citizen of the United States, residing at Philadelphia, in the county of Philadelphia and State of Pennsylvania, have invented 5 new and useful Improvements in Automatic Expansion Valve-Traps, of which the following is a specification.

My invention relates to that class of steam 10 valves which act automatically as a trap, to discharge the condensed water from steam pipes when the steam has been shut off.

With this end in view, I take or construct 15 any seated valve, remove the seat and cap and substitute therefor a seat of highly expansible metal through heat, such as aluminum, antimony, cadmium, zinc, etc., and a cap of non-expansible or nearly so metal, such as iron, cobalt, nickel, etc., for the purpose of automatically causing an opening 20 between cap and seat when condensed water collects in the steam pipe, and closing this opening when the water has been removed. I attain these objects by the mechanism and 25 parts illustrated in the accompanying drawing, in which:—

Figure 1, is a central section of an ordinary steam valve showing my invention in application. Fig. 2, shows my improved 30 valve seat and cap in a modified form. Fig. 3, is a sectional view of the valve spindle and the valve cap.

Referring now to the drawings for a further description of my invention; A, is the 35 casing of the valve with a web b and a valve seat rest C formed therein.

d is a neck formed on the casing to receive a screw cap d' in which a screw valve spindle d² operates to open or close the 40 valve. Between this spindle d² and screw cap d', is formed a stuffing box d³ in the well known manner.

The valve seat rest C is adapted to receive a valve seat S having a central opening s' and a flat top surface S² with a circular beveled edge S³. This valve seat S is made of a highly expansible metal and fits 45 loosely into the valve-seat rest C.

The valve spindle d² is provided with a 50 circular rim d⁴ and on to this rim is loosely fitted the valve cap n by means of the head n' with groove n², so that the cap n may be slipped from the valve spindle whenever it is desirable. The underside of the valve 55 cap is flat and has a triangular shaped rim fitting tightly against the beveled edge S²

of the valve seat S. This valve cap is made of nearly non-expansible metal and its underside fits exactly or is an exact counterpart of the valve seat S. The beveled edge 60 and triangular rim fitting over said edge are for the purpose of utilizing the expansion and contraction of the valve seat S in two directions, as the same will not only expand in the direction of its height but also 65 in diameter, the beveled edge will recede from the edge as the valve seat contracts and vice versa, as will be readily understood by those skilled in the art.

In Fig. 3 the contacting surfaces of the 70 valve seat and cap are in the shape of a frustum of a sphere and any other desirable shape may be given the contacting surfaces of the valve seat and its corresponding part.

The action and operation of my improved 75 automatic expansion trap valve when attached to a steam pipe, is as follows: Assuming that steam has passed through the valve in the direction shown by the arrow in Fig. 1, the valve is then shut tight by 80 turning the valve spindle d² and bringing the cap n into contact with the valve seat S. The steam in chamber A' of the valve will 85 gradually condense and water will be formed, cooling the valve seat S, which being expanded by the steam at the time of shutting the valve, will then contact and form an opening between the surface S² and the cap n, and the live steam back of the condensed water will force the latter 90 through this opening until the water is all disposed of when the live steam again will heat the expansible metal seat S causing the opening formed through the cooling of the seat, to be tightly closed. 95

It is to be observed that old valves of similar construction as shown in the drawing may easily be fitted with the improved valve seat and valve cap and be made to serve simply as an automatic steam trap; 100 and it is to be noted that in steam plants in use where valves of this nature without my improved valve seat and cap are installed for the purpose of blowing out the condensed water, these valves may instantly be 105 made automatic by fitting the same with my improved expansible valve seat and corresponding valve cap.

Having thus described the nature and object of my invention, what I claim as new 110 and desire to secure by Letters Patent is:

1. A valve trap having an inlet and outlet,

a valve seat rest formed between the same, a seat of expansible metal mounted in said rest, a valve cap of nearly non-expansible metal, means for operating the same, an undulated surface on the valve seat and a corresponding surface on the valve cap, said surfaces shaped to utilize the expansion or contraction of the seat in more than one direction, substantially as and for the purposes set forth.

2. A valve trap having an inlet and outlet, a valve seat rest formed between the same, a seat of expansible metal mounted in said rest, a beveled edge on the seat and a

central opening in said seat, a valve cap of nearly non-expansible metal, a triangular shaped rim on said cap adapted to fit over the beveled edge of the seat, and means for operating said cap substantially as and for the purposes set forth.

20

In witness whereof I have hereunto set my hand in the presence of two subscribing witnesses.

FREDERICK WM. RIESS.
